UNITED STATES PATENT OFFICE.

WILLIAM POOLE DRYER, OF SCHENECTADY, NEW YORK, ASSIGNOR TO GENERAL ELECTRIC COMPANY, A CORPORATION OF NEW YORK.

ELECTRIC SWITCH.

Application filed May 3, 1920. Serial No. 378,418.

To all whom it may concern:

Be it known that I, WILLIAM P. DRYER, a subject of the King of Great Britain, residing at Schenectady, county of Schenectady, State of New York, have invented certain new and useful Improvements in Electric Switches, of which the following is a specification.

My invention relates to electric switches, particularly to switches of the combined oil and air break type and has for its object to combine in one switch structure an air break switch element and an oil break switch element adapted to be operated in a definite sequence or operated independently under certain conditions.

It is often desirable to connect an oil break switch to a source of power or supply through an air break or disconnecting switch and in such cases, under present practice, it is customary to use independent switches for this purpose. In the novel form of switch of my invention, I combine in one unitary switch structure an oil break or main switch element with that of an air break or auxiliary switch element. In the case of high power installations the current is always interrupted at the main switch contacts. The principal functions of the auxiliary break are to insulate the main switch structure from the high potential line and to furnish a visible break so that this fact may be definitely and quickly determined. According to the inter-relation of the two switch elements, the auxiliary switch element is adapted to be controlled by the main switch element in such a way that the auxiliary element is operated to open its contacts after the main contacts open and closes its contacts prior to the closing of the main contacts or, if desired, the main switch element can be locked open or the auxiliary switch element may be held in either circuit opening or closing position independent of the main switch element.

The novel features which I believe to be characteristic of my invention will be definitely indicated in the claims appended here-to while the features of construction and mode of operation will be understood by reference to the following description taken in connection with the accompanying drawings which show the preferred embodiments of my invention and in which:

Figure 1 shows in side elevation, a switch

embodimenting the features of my invention in its circuit opening position; Fig. 2 is a side elevation of the switch of Fig. 1 in circuit closing position, Fig. 3 is a plan view of the switch mechanism in the position shown in Fig. 2, and Fig. 4 is a fragmentary sectional view taken on the line 4—4 of Fig. 1.

As shown in Fig. 1, I provide, combined in a single unitary switch structure, a main or oil break switch element 1 and an auxiliary or air break switch element 2. In describing the two elements of my switch as main and auxiliary elements, I desire it understood that I use these terms in the broadest meaning. The main switch element 1 comprises cooperating fixed and movable contacts 3 and 4 respectively, separable beneath the surface of an insulating fluid, such as oil, contained in a vessel 5. The movable contacts 4 are connected by the usual bridging member, carried at one end of a longitudinally movable rod 6, the rod carrying the movable contacts 4 into and out of engagement with fixed contacts 3 by means of an operating mechanism. This operating mechanism is of the usual type and in the embodiment shown, comprises a main operating member 7 pivotally mounted on a supporting frame 8 and adapted to be moved by a usual form of solenoid operating mechanism, as shown, which is held in circuit closing position and in effect supported in unstable equilibrium by a suitable latching means or toggle. The release of the latching means then permits the movement of the operating member 7 to circuit opening position. Carried by the oil vessel 5 are the usual terminal rods or members 9 for the main switch element, connected to fixed contacts 3 and supported by the usual insulating bushings. The main operating member 7 also carries, preferably integral therewith, an extension or control arm 10 which terminates in a plane engaging surface 11 and carries an ear or lug 12. The function of this arm 10 will be described herein-after.

The auxiliary or air break switch element 2 comprises cooperating fixed and movable auxiliary contacts 13 and 14 respectively, separable in air. The fixed auxiliary contacts 13 are shown, by way of example, as of the laminated brush type and are connected directly to the conducting members or plates 15 carried by insulators 16. Con-

ected also to members 15 are the main terminals 17 for the switch. The movable auxiliary contacts 14 are carried at the end of contact carrying arms or movable blades 18 and are resiliently supported thereon by springs 19. The arms 18 are pivotally mounted on the terminal members 9 for the main switch element 1 and in electrical connection therewith, a good electrical connection being insured by the auxiliary connections 20. The movable blades 18 are biased to circuit opening position by springs 21 and are connected for simultaneous movement by an insulating link 22 which serves to insulate the arms 18 from each other. The auxiliary or disconnecting switch element 2 therefore has its contacts 13 and 14 in series with the contacts 3 and 4 of the main or circuit breaker element 1 and located intermediate the main contacts and the terminals 17 for the switch. The energy of the circuit is interrupted by the main element 1 whereas the auxiliary element 2 interrupts no energy but merely removes potential from the main switch element.

For controlling the auxiliary switch contacts 13 and 14, I provide an auxiliary operating mechanism comprising an auxiliary or bell crank lever 23 pivotally supported on a shaft 24 and having an extended arm 25 provided near its end with a hole or opening 26, as best shown in Fig. 3. The bell crank lever 23 is biased to circuit opening position by means of a spring 27 surrounding shaft 24 but is prevented from moving too rapidly in circuit opening direction by a time delay device such as a dash pot 28 pivotally supported on the frame 8. The plunger of the dash pot 28 is connected by a shaft 29 to the arm 25 of lever 23, and arranged so that movement of lever 23 is retarded in circuit opening direction but not in circuit closing direction. The lever 23 is connected to one of the contact blades 18 through an insulating link 30 which serves to insulate the switch blades from the operating mechanism. The arm 25 of lever 23 terminates in a handle member 31 by means of which independent movement of the auxiliary switch mechanism may take place. The arm 25 also carries, extending at right angles to the handle 31, an arm 32 having an opening 33 therein, best shown in Fig. 3. Depending from arm 25 is a lug 34 adapted to cooperate with lug 12 of arm 10, as will be described.

Mounted adjacent arm 25 and pivotally supported on the shaft 24 is an auxiliary operating lever or member 35 for the auxiliary operating mechanism, as best shown in Fig. 3. Member 35 is provided at its free end with an opening or hole 36 adapted to register with the opening 26 of arm 25. The operating member 35 also carries a roller

bearing 37 cooperating with the engaging 65 surface of arm 10 as will be described.

The auxiliary operating member 35 is controlled by the main operating member 7 of switch element 1 by means of the control arm 10 and its plane engaging surface 11 70 which cooperates with the roller bearing 37. In moving the main operating member 7 from the position shown in Fig. 1 into switch closing position, shown in Fig. 2, its initial movement causes the plane surface 75 11 of arm 10 to engage the roller bearing 37 of the auxiliary operating member 35 and move member 35 into circuit closing position, prior to the closing of the main contacts 3 and 4. Further movement of 80 the main operating member 7 to circuit closing position causes the plane surface 11 of arm 10 to move freely under the roller bearing 37 to the position shown in Fig. 2, in which position the arm 10 serves to hold 85 the arm 35 in circuit closing position. In opening the switch, the plane surface 11 is so shaped that it holds the auxiliary operating member 35 in its circuit closing position until after the main contacts 3 and 4 90 have separated whereupon during the final movement of the main operating member 7 to its circuit opening position, the plane surface 11 is moved free of the roller bearing 37 and operating member 35 is 95 then free to move to circuit opening position.

The auxiliary operating member 35 according to my invention is detachably secured to its operating mechanism for the auxiliary switch element 2 or to the bell crank lever 23 by means of a removable pin 38 adapted to be inserted in the opening 26 of bell crank arm 25 and opening 36 of operating member 35. With the pin 38 inserted in these openings, as best shown in Fig. 3, auxiliary operating member 35 is rigidly connected to arm 25 of the bell crank lever 23, and the auxiliary switch contacts 13 and 14 are thereby controlled by member 35 in response to the main switch element 1 or operating member 7, so that the main and auxiliary contacts are opened and closed in the definite sequence described. The pin 38 terminates in a wing nut 39, to which is secured a yoke 40. The yoke 40 is provided to cooperate with arms having openings therein through which a padlock may be inserted to prevent the removal of the pin by unauthorized persons. In the arrangement shown in Fig. 3, operating arm 35 carries an extension 41 having an opening 42 therein. Yoke 40 is moved over extension 41 so that a lock inserted in opening 42 holds the yoke 40 in position and prevents the removal of the pin 38.

Should it be desired, however, to operate the main or oil break switch element inde-

pendent of the auxiliary air break switch element 2, it is only necessary to remove the pin 38 from openings 26 and 36 so that the auxiliary operating member 35 is detached 5 from bell crank lever 23 and its mechanism. The operation of the main operating member 7 under these conditions, operates the auxiliary operating member 35 as before, but as member 35 is not connected to 10 the bell crank arm 25, the member 35 merely moves idly without affecting the auxiliary switch element.

For various reasons, it may be desirable 15 to hold or lock the auxiliary switch element 2 in either its circuit opening or closing positions independent of the main switch element 1, and for this purpose I provide means comprising a frame member 43 preferably part of the switch support and located adjacent the ends of arm 25 of bell 20 crank lever 23 and the end of auxiliary operating member 35. This frame 43 is provided with two openings or holes 44 and 45. Opening 44 is in alignment with opening 26 in arm 25 when the arm is in circuit closing position and opening 45 is in alignment with opening 26 when the arm is in its circuit opening position. To lock or hold the auxiliary switch element 2, therefore, 25 in its circuit closing position, it is only necessary to insert pin 38 from the front of frame 43 so that it extends through opening 44 therein and through opening 26 in arm 25. The auxiliary switch element 2 is thereupon held inoperative and independent 30 of the main switch element 1 which is, however, free to open and close. To hold the pin 38 in position, its yoke 40 is slipped over arm 32, best shown in Fig. 3, so that a lock 35 may be inserted in opening 33 of the arm. To lock the auxiliary switch element 1 in its circuit opening position, pin 38 is inserted in opening 45 of frame 43 and opening 26 of arm 25 whereupon the auxiliary 40 switch element is held inoperative and independent of the main switch element. If desired, the auxiliary operating member 35 may also be locked in its circuit closing position by extending the pin 38 to engage opening 36 of the member 35.

In order to prevent the unauthorized closing of the auxiliary switch element 2 by the handle 31 when the main switch element is closed, I provide an interlocking means 45 which comprises the lug 12 on control arm 10 and lug 34 on the arm 25. With the main switch element 1 in circuit opening position, as shown in Fig. 1, the auxiliary switch element 2 may be opened and closed 50 at will by handle 31. Should, however, the main switch element 1 be closed, lug 12 moves into the path of lug 34 so that the lifting of handle 31 to close the auxiliary switch element moves lug 34 into engage-

ment with lug 12 and the closing of the auxiliary switch element is prevented. Suppose both switch elements 1 and 2 are closed, as shown in Fig. 2, if the handle 31 is moved in an attempt to open the auxiliary switch element, lug 34 immediately 70 strikes lug 12 on arm 10 and the auxiliary switch is prevented from opening.

I also provide a means for locking the main switch element 1 in its circuit opening position which consists of an arm 46 carried by the support 8 and provided with two openings 47 and 48. As best shown in Fig. 1, the pin 38 is inserted through opening 42 in extension arm 41 carried by the auxiliary operating member 35 and through 80 opening 47 in arm 46 to lock the auxiliary operating member in its circuit opening position. The yoke 40 of pin 38 is put over the end of arm 46 and a lock adapted to be inserted in opening 48 to prevent the unauthorized closing of the switch. Should an attempt be made to close the main switch element 1, the end of control arm 10 strikes the roller bearing 37; and, as member 35 is locked in position, the roller bearing prevents 90 the main switch element from moving to circuit closing position.

What I claim as new and desire to secure by Letters Patent of the United States, is—

1. An electric switch comprising two co-operating sets of contacts connected in series, one set of contacts separable in oil and the other set of contacts separable in air; an operating mechanism for each set of contacts, and means for at will rendering the operating mechanism for said air break contacts operative in response to the operating mechanism for said oil break contacts in a definite sequence or for holding the operating mechanism for said air break contacts in open or closed position independent of the operating mechanism for said oil break contacts.

2. An electric switch comprising a circuit breaker element having contacts separable in oil, an operating mechanism therefor, a disconnecting switch element mounted on the terminals of said circuit breaker element having contacts separable in air, and means for operating said switch element in response to the operation of said circuit breaker element whereby said elements are opened and closed in a definite sequence, and means for at will holding said switch element in open or closed position independent 120 of the movement of said circuit breaker element.

3. An electric switch comprising a main operating member, contacts controlled thereby, an arm carried by said member, an auxiliary operating member biased to circuit opening position but movable to closing position in response to the initial movement

- 4
- of said arm in circuit closing direction, said arm operating to permit the movement of said auxiliary member to circuit opening position as said main operating member completes its circuit opening movement, a mechanism adapted to be detachably secured to said auxiliary operating member, and contacts controlled by said auxiliary member.
5. In combination, a main switch element having contacts separable in oil, an auxiliary switch element having contacts separable in air, means controlled by said main element for moving said auxiliary element to circuit closing position prior to the closure of said main element and holding said auxiliary element ineffective to move to circuit opening position until subsequent to the opening of said main element, and means for at will holding said auxiliary element in open or closed position independent of said main element.
6. In combination, two separate switch elements, one having contacts separable in oil and the other having contacts separable in air, said contacts being connected in series, an operating member for said air break element controlled by said oil break element, means operative in response to said oil break element for moving said operating member to circuit closing position prior to the closure of said oil break element and for holding said operating member in circuit closing position until said oil break element has moved to circuit opening position, and a mechanism for said air break element detachably secured to said operating member for at will maintaining said air break element independent of said oil break element.
7. An electric switch comprising main contacts separable in oil, a main operating mechanism for said contacts, terminal members for said switch, auxiliary contacts intermediate said terminals and said main contacts separable in air, an auxiliary mechanism for controlling said auxiliary contacts, and means carried by said main operating mechanism for causing said auxiliary mechanism to close said auxiliary contacts prior to the closing of said main contacts and for holding said auxiliary mechanism in closed position until said main contacts have separated.
8. An electric switch comprising contacts separable in oil, a main operating member controlling said contacts, a second operating member carrying a roller bearing and biased to circuit opening position, an arm carried by said main operating member terminating in a plane engaging surface which cooperates with said roller bearing to move said second operating member to circuit closing position, said arm acting to hold said second operating member in circuit closing position until said main operating member moves to circuit opening position, a mechanism controlled by said second operating member, and auxiliary contacts controlled by said mechanism separable in air.
9. An electric switch comprising contacts separable in air, a mechanism controlling said contacts, an operating member detachably secured to said mechanism, a second set of contacts separable in oil, a mechanism for controlling said second set of contacts including a separate operating member, means carried by said separate operating member for moving said first operating member to cause said contacts to open and close in a definite sequence, and means for locking the mechanism for said air break contacts in open or closed position independent of the operation of said separate operating member.
10. In an electric switch, the combination with cooperating fixed and movable main contacts separable in oil, an operating member controlling said contacts, an arm carried by said member and terminating in a plane engaging surface, terminal members connected to said fixed contacts, auxiliary movable contacts pivotally mounted on said terminal members, fixed contacts cooperating with said movable auxiliary contacts, an auxiliary operating member for said auxiliary contacts having a roller bearing engaging said plane surface to hold said auxiliary member in circuit closing position, said auxiliary member being biased to move to circuit opening position when said plane surface is carried by said arm to circuit opening position, and a mechanism controlling said auxiliary contacts detachably secured to said auxiliary operating member.
11. In an electric switch, the combination with a main switch element comprising contacts separable in oil, and an operating mechanism controlling said contacts including an operating member, of an auxiliary switch mechanism carried by said main switch element comprising contacts separable in air, an operating mechanism controlling said auxiliary switch element, said

- operating mechanisms being so interrelated that the main switch element opens prior to the opening of said auxiliary switch element and closes after said auxiliary switch element closes, and means for locking said auxiliary switch element in open or closed position independent of said main switch element.
12. An electric switch comprising a main switch element having contacts separable in oil, an operating mechanism controlling said contacts, an auxiliary switch element having contacts separable in air, means for moving said auxiliary switch element to circuit opening position in response to the final movement of said operating mechanism into circuit opening position and for moving said auxiliary switch element to circuit closing position in response to the initial movement of said mechanism in circuit closing direction, and means operative to hold said auxiliary switch element in either open or closed position independent of said main switch element.
13. An electric switch comprising two switch elements, one separable under oil and the other separable in air, means for effecting the operation of said air break element in response to the operation of said oil break element to cause said elements to open and close in a definite sequence, means for preventing the closure of said oil break element while said air break element is open, and means for preventing the closure of said air break element when said oil break element is closed.
14. An electric switch comprising a current interrupting switch element and a disconnecting switch element, and mechanism connecting said elements which will cause the closure of the disconnecting switch element before the closure of the current interrupting element and permit the disconnecting element to open only after the opening of the current interrupting element.
15. An electric switch comprising a current interrupting switch element and a disconnecting switch element, the latter element being biased to open position and mechanism which will cause the closure of said disconnecting element and the subsequent closure of said current interrupting element and will cause the opening of said current interrupting element and permit the subsequent opening of the disconnecting element.
16. A switch comprising a main switch element and an auxiliary switch element, the latter element being biased to open position, connecting means between said elements which will operate to cause said auxiliary element to close and subsequently to cause said main element to close and will cause said main element to open and subsequently will permit said auxiliary element to open, and means for rendering said connecting means inoperative to cause movement of said auxiliary means.
17. A circuit breaking apparatus of the character described comprising an oil switch mechanism, automatically opened switch mechanism exteriorly of said oil switch, said switch mechanisms being serially included in the same circuit, and means for actuating both said switch mechanisms comprising a series of levers held in unstable equilibrium when said switches are closed.
18. A circuit breaking apparatus of the character described comprising an oil switch mechanism, an air break switch mechanism automatically controlled thereby, means for actuating said air break mechanism comprising a series of levers supported in unstable equilibrium when said air break is closed, means whereby the support for said actuating means is withdrawn when said oil switch is opened to open said air break, and means for retarding the opening movement of said air break mechanism.
19. A circuit breaking mechanism of the character described comprising an oil switch and mechanism for actuating the same, an air break switch and mechanism for actuating the same associated with said oil switch actuating mechanism and normally automatically controlled thereby, and means for disestablishing the automatic control of said air break switch actuating mechanism by said oil switch actuating mechanism.
20. A circuit breaking mechanism of the character described comprising an oil switch and mechanism for actuating the same, an air break switch and mechanism for actuating the same associated with said oil switch actuating mechanism and normally automatically controlled thereby, and means for locking said air break switch actuating mechanism to hold said air break switch in closed position so that said oil switch actuating mechanism may be operated independently thereof.
21. A circuit breaking mechanism of the character described comprising an oil switch mechanism, an air break mechanism associated with said oil switch mechanism and normally automatically controlled thereby, and means for simultaneously locking both of said switch mechanisms in open position.
22. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, and means cooperating with the free end of said arm for locking both of said switch mechanisms in open position.
23. A circuit breaking apparatus of the character described comprising an oil switch mechanism, automatically opened air break

- switch mechanism exteriorly of said oil switch, said switch mechanisms being serially included in the same circuit, means for actuating each of said switch mechanisms comprising a series of levers supported in unstable equilibrium when said oil switch is closed, and interengaging means on said actuating means whereby the removal of the supporting means of the oil switch actuating means will remove the support for the air break actuating means to open said air break.
24. A circuit breaking apparatus of the character described comprising an oil switch mechanism, an air break switch mechanism automatically controlled thereby, means for actuating said air break mechanism comprising a series of levers supported in unstable equilibrium when said air break is closed, and means whereby the support for said actuating means is withdrawn when said oil switch is opened to open said air break.
25. A circuit breaking mechanism of the character described comprising an oil switch mechanism, an air break mechanism associated with said oil switch mechanism and normally automatically controlled thereby, and means for operating said switch mechanisms independently of each other to open and close the oil switch mechanism when the air break mechanism is open or closed and to open and close the air break mechanism when the oil switch mechanism is open.
26. A circuit breaking mechanism of the character described comprising an oil switch mechanism, an air break mechanism associated with said oil switch mechanism and normally automatically controlled thereby, and means for locking said air break mechanism in open position so that said oil switch mechanism may be manipulated independently thereof without closing the circuit comprising said oil and air break mechanisms.
27. A circuit breaking mechanism of the character described comprising an oil switch mechanism, an air break mechanism associated with said oil switch mechanism and normally automatically controlled thereby, and means for locking said oil switch mechanism in open position so that said air break mechanism may be manipulated independently thereof without closing the circuit comprising said oil and air break mechanisms.
28. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, and means cooperating with the free end of said arm for disestablishing the automatic control of said air break mechanism by said oil switch mechanism.
29. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, and means cooperating with the free end of said arm for locking said air break mechanism in closed position so that said oil switch mechanism may be operated independently thereof.
30. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, and means cooperating with the free end of said arm for locking said air break mechanism in open position so that said oil switch mechanism may be operated independently thereof without closing the circuit comprising said oil and air break mechanisms.
31. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, said arm being provided with a portion extending forwardly from the pivot thereof, a stationary arm mounted on the switch framework and means for locking said operating arm to said stationary arm in a plurality of positions.
32. A circuit breaking mechanism of the character described comprising an oil switch mechanism, an air break mechanism associated with said oil switch mechanism and normally automatically controlled thereby, said air break mechanism comprising an operating arm pivotally mounted on the switch frame, said arm having a portion extending forwardly from its pivot, said forwardly extending portion being provided with an opening, a stationary arm mounted on the switch framework and provided with openings with which the opening in said operating arm is adapted to be aligned, and means adapted to be passed through a pair of aligned openings to lock said operating arm in a plurality of positions.

In witness whereof, I have hereunto set my hand this 1st day of May, 1920.

WILLIAM POOLE DRYER.
